UNITED STATES PATENT OFFICE

92,049

DESIGN FOR A STANDARD FOR A FOOD MIXING DEVICE

Walter Van Guilder, Stratford, Conn., assignor
to General Electric Company, a corporation of
New York

Application May 25, 1933, Serial No. 48,210

Term of patent 14 years

To all whom it may concern:

Be it known that I, WALTER VAN GUILDER, a citizen of the United States, residing at Stratford, County of Fairfield, State of Connecticut, have invented a new, original, and ornamental Design for a Standard for a Food Mixing Device, of which the following is a specification, reference being had to the accompanying drawing, forming a part thereof.

The accompanying drawing shows in Fig. 1 a

side perspective view, in Fig. 2 a front perspective view, and in Fig. 3 a plan view of a standard for a food mixing device embodying my new design.

I claim:

The ornamental design for a standard for a food mixing device substantially as shown.

In witness whereof, I have hereunto set my hand this 17th day of May, 1933.

WALTER VAN GUILDER.
